(57) **CLAIM**

The ornamental design for a case for electronic device with flexible multi-configuration stand, as shown and described.

DESCRIPTION

FIG. 1 is a front perspective view of a case for electronic device with flexible multi-configuration stand shown in an open state for use, shown with an environmental electronic device installed within;

FIG. 2 is a front elevation view of the case for electronic device with flexible multi-configuration stand of FIG. 1, shown without the electronic device;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a rear perspective view thereof;

FIG. 9 is a second front perspective view of the case for electronic device with flexible multi-configuration stand of FIG. 1, shown in a closed state;

FIG. 10 is a third front perspective view of the case for electronic device with flexible multi-configuration stand of FIG. 1 in an alternate open state for use, shown with an environmental electronic device installed within;

FIG. 11 is a right-side elevation view thereof;

FIG. 12 is a fourth front perspective view of the case for electronic device with flexible multi-configuration stand of FIG. 1 in another alternate open state for use, shown with an environmental electronic device installed within;

FIG. 13 is a right-side elevation view thereof;

FIG. 14 is a fifth front perspective view of the case for electronic device with flexible multi-configuration stand of FIG. 1 in another alternate state for use, shown with an environmental electronic device installed within;

FIG. 15 is a right-side elevation view thereof;

FIG. 16 is a sixth front perspective view of the case for electronic device with flexible multi-configuration stand of FIG. 1 in another alternate state for use, shown with an environmental electronic device installed within; and,

FIG. 17 is a right-side elevation view thereof.

The broken lines in FIGS. 1, 10, 12, 14, and 16 showing the electronic device installed inside the case depict environmental subject matter only and form no part of the claim, while all other broken lines depict portions of the case for electronic device with flexible multi-configuration stand that form no part of the claimed design.
